The ornamental design for an interbody implant, as shown and described.

DESCRIPTION

FIG. 1 is a perspective view of an interbody implant showing an abutment only.

FIG. 2 is a front elevation view thereof. A rear elevation view is a mirror image of the front elevation view.

FIG. 3 is a left side elevation view thereof.

FIG. 4 is a right side elevation view thereof.

FIG. 5 is a top plan view thereof.

FIG. 6 is a bottom plan view thereof.

FIG. 7 is an enlarged cross-sectional view taken along 7-7 in FIG. 2.

FIG. 8 is a cross-sectional view taken along 8-8 in FIG. 6; and,

FIG. 9 is a cross-sectional view taken along 9-9 in FIG. 6. The portion of the interbody implant shown in broken lines is for the purpose of showing environmental structure only and forms no part of the claimed design.
